(57) **CLAIM**

The ornamental design for a marker cap leash, as shown and described.

DESCRIPTION

FIG. 1 is a top perspective view of a marker cap leash, showing our new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The dash-dash broken lines depicting a marker and elephant is for the purpose of illustrating environmental structure and form no part of the claimed invention. The dot-dash broken lines define the bounds of the claimed design and form no part thereof.
